UNITED STATES PATENT OFFICE.

MIKE HUFFMAN, OF DES MOINES, IOWA.

BOILER CLEAN-OUT DEVICE.

Application filed June 15, 1921. Serial No. 477,806.

To all whom it may concern:

Be it known that I, MIKE HUFFMAN, a citizen of the United States, and resident of Des Moines, in the county of Polk and State 5 of Iowa, have invented a certain new and useful Boiler Clean-Out Device, of which the following is a specification.

My invention relates to and consists in certain improvements on boiler clean-out devices of the class illustrated in my Patent 10 Number 974,064, issued October 25, 1910.

The object of my present improvement is to provide means for thoroughly and quickly removing sediment from the bottom of the 15 boiler with the use of a less quantity of water from the boiler than has heretofore been employed, to thereby effect an economy in the operation of these devices by the saving of a large part of the previously 20 heated water which has been necessary heretofore in effecting a thorough cleaning of the boiler.

My invention consists in the construction 25 of a device to be used in the nature of an attachment for boiler cleaning-out devices, which attachment is of simple, durable and inexpensive construction, and easily applied, as hereinafter more fully set forth, pointed out in my claim, and illustrated in the accompanying drawings, in which:

Figure 1 shows an ordinary form of steam boiler having a clean-out device therein with my attachment applied thereto.

Figure 2 shows an enlarged, detail, trans- 35 verse, sectional view showing a portion of the bottom of the boiler and the clean-out pipe adjacent thereto, and my improved attachment applied to the clean-out pipe; and

Figure 3 shows a perspective view illustrating 40 my improved attachment applied to a clean-out pipe.

Referring to the accompanying drawings, I have used the reference numeral 10 to indicate a boiler of the return flue type.

The clean-out device comprises a stationary pipe 11 permanently supported within the boiler in position slightly spaced above the bottom of the boiler. In the bottom of the pipe 11 is a slot 11^a. This pipe extends 45 through one end of the boiler to a point outside of the rear furnace wall where it is provided with a discharge valve 12.

Within this stationary pipe 11 is a rotatable pipe 13 having a series of slots 14 out 50 of line with each other. This rotatable pipe 15 is provided at its rear end beyond the rear

furnace wall with a hand wheel 15 by which it may be turned.

The operation of this clean-out device is 60 as follows:

When a small amount of sediment has become deposited in the bottom of the boiler below the clean-out device, the valve 12 is opened and the hand wheel 15 turned. This 65 brings some of the slots 14 successively into alignment with the slot 11^a, and the pressure of the steam within the boiler violently forces the water from the boiler through said slots and out through the valve 12 to a point of discharge, and this violently moving current of water picks up and carries 70 with it the sediment adjacent to the slot in the stationary blow-off pipe.

Devices of the class just described are now 75 in general use, and their construction and operation are well known.

My improvement consists of a deflector plate comprising a body portion 16 made of sheet metal and resting on top of the stationary pipe 11 and extending throughout 80 the length of said pipe within the boiler. It is secured to the pipe at suitable intervals by U-bolts 17. Its sides are inclined downwardly and outwardly from the top of the pipe 11 to a point spaced apart from 85 the bottom of the boiler substantially to the same amount as the bottom of the pipe 11 is spaced from the bottom of the boiler.

Supporting legs 18 are provided in the 90 lower edge of the deflector plate to engage the bottom of the boiler, and thus firmly hold the deflector plate in position. I also preferably provide a series of small circulating openings 19 in the deflector plate 95 near its top.

Heretofore, and without my improved deflector plate it was possible to remove the sediment from the boiler, but the current of water under pressure passing from the boiler required an excessive amount of time 100 and an excessive amount of heated water before it thoroughly removed that part of the sediment that stood spaced several inches from the slot in the blow-off pipe, and since the discharge of the heated water had 105 to be compensated for by a fresh charge of cold water, and this cold water had to be heated, the operation of cleaning out was too expensive.

By the use of my improved deflector plate, 110 when the slots 11^a and 14 are brought together and the valve 12 is opened, the pres-

sure of steam within the boiler violently forces the water through said slots and creates a current flowing from the sides of the boiler downwardly and inwardly to the center of the boiler, and the edges of the deflector plate cause this current of water to travel close to the boiler adjacent to its body, and thereby create a current of water that travels right through the deposits of sediment instead of over the top of said deposits, and this causes all of the sediment to be removed very rapidly and with a minimum loss of hot water.

Furthermore, by having the deflector plate curved as shown in the drawings, these currents of water coming down the sides of the boiler toward the center will be caused by the edges of the deflector plate to have a circular whirling motion under the deflector plate, which rapidly stirs up sediment and carries it out through the slots, as shown by the arrows in Figure 2.

The circulating openings 19 form an important function of a device of this kind,

because they are large enough so that they will not materially interfere with the ordinary circulation of water from the bottom of the boiler upwardly, when the blow-off device is closed. When the blow-off device is open, these holes do not have sufficient capacity to materially effect the travel of the greater body of water under the edges of the deflector plate and toward the blow-off slots.

I claim as my invention:

The combination with a boiler clean-out device of the class described, of a deflector plate secured to the boiler clean-out device having its top inclined downwardly and outwardly toward the bottom of the boiler, and its edges spaced from the bottom of the boiler, and circulating openings formed in said plate, and supporting legs at the edges of the plate to engage and rest upon the bottom of the boiler.

Des Moines, Iowa, May 27, 1921.

MIKE HUFFMAN.
